[57] CLAIM

The ornamental design for a frame unit for truck bed
cover, as shown and described.

DESCRIPTION

FIG. 1 is a rearward, downward perspective view of a
frame unit for truck bed cover showing the new design;
FIG. 2 is a forward, downward perspective view
thereof.

The broken line showing of a portion of a pickup truck
is for illustrative purposes only and forms no part of the
claimed design.

FIG. 1

FIG. 2
